SELF-LEVELING DEVICE FOR ELECTRIC
ELEVATORS

Emil Drenker, Thornwood, N. Y.

Application February 23, 1937, Serial No. 126,992

1 Claim. (Cl. 187—29)

This invention relates to elevators and more particularly to such as use cars for the delivery of passengers and freight at selected landings.

Such cars, while under the control of an operator, frequently fail to come to a stop at the exact level of the landing, requiring restarting in one direction or the other in order to bring the floor of the car even with the floor of the building, necessitating delay and inconvenience, even 10 with experienced operators.

It is therefore an object of the invention to provide an effective, electrically operated device which automatically causes an elevator car to come to a full stop when its floor arrives at a 15 level with the floor of the landing, irrespective of the weight of its load.

A further feature is in the provision of a device which can be readily applied to elevators already in use, or to new installations, whereby a positive 20 floor levelling effect is obtained.

These and other objects, which will become manifest as the description progresses, are attained by the novel and practical construction, combination and arrangement of parts herein- 25 after described and illustrated in the accompanying drawings, constituting a material component of this disclosure, and in which:—

Figure 1 is a partial side elevational, partial sectional view of an embodiment of the invention showing its structural features.

Figure 2 is a vertical sectional view taken on line 2—2 of Fig. 1.

Figure 3 is a diagrammatic view in front elevation of a conventional elevator and its guide-way, showing an application of the device.

Figure 4 is a schematic view of the electric wiring system.

Referring in greater detail to the drawings, Figure 3 shows the usual upright rigid runways 40 extending through the several floors and acting as guides for a car 16 having a platform 17 and crosshead 18 from which extend clips 19 to engage the runways 15.

Secured on the cross-head 18, at one end, is a 45 plate 20 to which is bolted a plate arm 21 having downturned lugs 22—23 drilled to receive a hinge pin 24 on which is mounted a hub 25, having upright and horizontal plate arms respectively 26—27.

An arm 28 extends from the lugs 22, opposite the arm 21 and is provided with an adjustable stop screw 29 to limit the downward movement 50 of the horizontal plate arm 27.

Raised from the lug 22 is a bracket 30 terminating in an elongated bearing 31 having a ro-

tatable sleeve 32, in which is mounted a spindle 33, provided with collars 34—35 set-screwed thereto to prevent endwise movement.

A lever 38 is adjustably set screwed to the sleeve 32, between the end of the bearing and the collar 35, and a corresponding lever 40 is held on the extending end of the spindle 33.

Rotatably carried at the end of the lever 38 is a roll 39 and a similar roll 41 is mounted on the end of the lever 40.

Carried by a webbed portion 30 of the plate arm 26 are spaced members 43—45, rockingly mounted on the axis of the spindle 33, their lower portions being pressed outwardly by springs 44 set in the plate arm.

These members have fixed in them, in register with the springs 44, bolts passing through the lower elements 46 of levers 47—48, the lever 47 being set-screwed to the spindle 33 and the other lever 48 correspondingly secured to the sleeve 32.

The action of these levers is limited by reason of their ends 46 extending into a recess 49 and can be adjusted by nuts on the bolts.

The extreme upper ends of the levers 47—48 are provided with non-conducting bushings 50 through which slidably pass spindles 51 having contact heads 52—53 normally pressed outwardly by springs.

An upright plate 55, of non-conducting material, is bolted to an upstanding portion of the plate arm 27 and carries, at its upper portion, contacts 57—58 connected by looped conductors.

The levers 47—48 are pressed outwardly to bring the contacts into engagement by compression springs 60 set in recesses in the members 43—45.

In order to cushion and delay the movement of these levers, dash pot casings 62 are fixed on the rear side of the plate 55 and operable therein are plungers 63 pressed rearwardly by springs 64, 40 controllable vents 65 being provided for the escape of air as the plungers are forced into the dash pots.

Stems 66, provided with flattened outer ends 67, containing slots 68, are passed through the plate 55 to abut the plungers, these stems being actuated by pins 69 set in the levers 47—48.

Mounted on the plate arm 21 is an electromagnet 70 having an armature 71, its outer extending end making operative contact with the 50 horizontal plate arm 26 whereby the plate arms and elements associated with them are tilted on the axis 24.

Adjustably attached to car guide-ways, or other convenient adjacent points, are rigid cams 75—76, 55

the cam 75 being positioned to engage the roll 41 and the cam 76 to engage the roll 39, these cams being disposed on all floors except the extreme top and bottom.

Carried by the plate 55 is a switch 77 controlling current to the contact 57, a similar switch 78 controlling the contact 58, while a third intermediate switch 79, controls current to the electromagnet 70 and is used when the levers are in neutral position.

Referring now to the wiring diagram, seen in Figure 4, an electric current enters the device by wire 80, passing through a fuse 81 to a switch 82, thence to the motor control arms 83—84 turnable on the axis 85 and carrying contacts one of which is connected to a conductor 90 having a manually operable switch 91 and car-gate or door operated switch 92, the conductor eventually leading to the solenoid 70.

A branch 95 of the conductor 90, is further branched, as at 96—97, the former supplying current to the contact 53 the circuit between contacts 53 and 58 being automatically closed when the roll 39 is passed by the cam 76; the branch 97 conveys current to the contact 52 the circuit between contacts 52 and 57 being closed when roll 41 is passed by the cam 75.

Return current from the contact 58 is conducted by wire 100 to switch 101, thence through solenoids 102—103 to switch 104.

A branch 105 of the wire 100 leads to a controller contact arm 106 contactable by the movable motor control arm 84 when a slow rate of speed is required in upward travel of the car.

A higher speed is obtained by moving the controller arm 84 further to engage another controller contact arm 107, connected by wire 108, passing through a solenoid 109, which weakens the shunt field of the car motor, and is joined to a wire 110 connecting the solenoids 102—103.

A branch 111 of the conductor 108 leads to a high speed controller contact arm 112 engageable by the movable motor control arm 83, adjacent to which is a slow speed contact arm 113, connected by wire 114 to the switch 104, while a branch 115 of the wire 114 leads to the car carried contact 57.

A wire 116 leads from the solenoid 109, provided with a switch 117, the wire being connected

with a fuse 118 and leads to the main supply line.

A branch 119 of the wire 116 is provided with a switch 120 and leads to the solenoid 70, thereby completing the circuit.

In operation, when the car 16 is started in either direction, up or down, the door being closed, closing the switch 92 and retiring the rolls to avoid striking the cams on the floors to be passed.

When the car control lever is moved into neutral position, in order to make a stop on the desired floor, the electromagnet 70 will become energized, drawing the switch contacts into operative positions.

If the car moving up stops at too high a level, the up switch stays in off position, while the down switch makes contact and brings the car to a level stop; in moving down the same effect is produced in a reverse manner. When the car door is opened the contacts carried by it break the circuit on the shunt line and the switches return to an off position.

Having thus described the invention and set forth the manner of its construction and application, what is claimed as new and sought to obtain by Letters Patent, is:—

In an electric elevator movable between fixed upright guide rails, said elevator comprising a car having a crosshead, a plate secured to said crosshead, an electromagnet on said plate having an axial armature disposed horizontally, an arm extending outwardly from said plate provided with an adjusting screw, a bracket having two arms disposed at a right angle pivoted in said plate, one of said arms in register with said armature and the other with said adjusting screw, a shaft journaled in said bracket, a sleeve circumjacent the shaft, levers fixed respectively on said shaft and sleeve, rolls rotatably mounted on the ends of said levers, cams fixed on said rails in register with said rolls, resilient means to cushion the action of said levers when moved in either direction, spring actuated dash pots combined with said resilient means whereby said levers are cushioned near the limits of their movement, means actuated by said levers to control the elevator car motor, and selective control means for said electromagnet carried in said car.

EMIL DRENKER. 50
